UNITED STATES PATENT OFFICE.

EUGENE C. HERTHEL, OF CHICAGO, ILLINOIS, ASSIGNOR TO SINCLAIR REFINING COMPANY, OF NEW YORK, N. Y., A CORPORATION OF MAINE.

PROCESS FOR PRODUCING LIGHT HYDROCARBON LIQUIDS.

Application filed April 4, 1925. Serial No. 20,641.

This invention relates to improvements in the production of light hydrocarbon oils, and particularly light gasolines, or oils containing increased proportions of light gasoline constituents, by the distillation of heavier hydrocarbon oils under pressure.

The straight-run gasolines produced in the distillation of petroleum oils, and gasolines produced by cracking processes such as pressure distillation, with the methods customarily employed, usually contain an amount of very light easily vaporizing constituents somewhat less than is desired for certain purposes, such as for use as motor fuel. Because of this deficiency of ordinary gasolines, it has been customary for refiners to blend with their straight-run or cracked gasolines varying proportions of very light oils such as those recovered from natural gas and casing-head gas and commonly known as natural gas gasoline, casinghead gasoline and natural gasoline. While these very light oils are available in the various gas and oil fields, special methods of recovery are required for separating and recovering them from the gas mixtures in which they occur, and enormous losses by vaporization are usually involved in handling such very light oils from production through the refinery. Not only are evaporation losses high, but, due to the high vapor pressures and the inflammability of these very light oils, danger is involved in handling them, with the consequence that initial recovery, shipment and storage, and handling in blending, and refining, of these very light oils become expensive.

Among the objects of this invention is the provision of an improved method for producing such very light hydrocarbon oils, or such light oil constituents, in the refinery, which avoids the disadvantages incident to such light oils as hitherto available in production, handling, storing and shipping. In one aspect, the present invention provides an improved method for the production in the refinery of such very light oil stocks which may be employed as required, for example, in blending operations as previously practiced. In another aspect, this invention provides an improved method for increasing the amount of very light and easily vaporizing constituents in gasolines, or pressure distillates, produced in cracking operations. Such oils, having an increased content of

very light components, may also be employed for blending with other heavier oils, or the operation may be regulated, in accordance with this invention, for the direct production of a distillate having the desired characteristics, particularly as to the content of very light and easily vaporizing constituents.

According to the present invention, a heavy oil is subjected to pressure distillation, and the pressure distillation is regulated in an improved manner to obtain a pressure distillate containing very light constituents in increased concentration.

In carrying out the present invention, a heavy but easily cracked oil, such as coke still gas oil or gas oil of high wax content, is subjected to distillation under pressure with a mild application of heat, and very light constituents are concentrated in the distillate by subjecting the vapors to a refluxing operation which is regulated to permit only a limited amount of the vapors to pass off as distillate. If such easily cracking stocks are subjected to extreme cracking temperatures, an excessive formation of gas and coke results, but with a mild application of heat the amount of gas and coke formation may be restricted while a tendency to form very light constituents is developed. Also, according to the present invention, the refluxing operation is regulated so that a much higher proportion of the vapors, and particularly of the heavy components of the vapors, is returned to the pressure distillation than is common in refluxing operations employed in conjunction with pressure distillation processes. This refluxing of the vapors may be effected by external cooling of the vapors, but it is more advantageously effected by the introduction of fresh oil to be supplied to the pressure distillation into direct contact with the vapors, the reflux together with the admixed fresh oil then being returned to the pressure still. If the increased refluxing employed in carrying out the present invention tends to choke the pressure still because of the return in large amounts of intermediate light constituents, the pressure is somewhat increased.

Where the refluxing is effected by the direct introduction of fresh oil into the vapors from the pressure still, oil at ordinary temperature is supplied to the refluxing operation at a rate of from about 190% up to 300% or more of the rate at which distillate

- is taken off, and the refluxing operation is controlled by regulating the rate at which the fresh oil is supplied thereto. For example, the supply of fresh oil to the refluxing operation may be regulated in accordance with the temperature at which the vapors forming the distillate escape from the refluxing operation. With this large amount of cool fresh oil introduced into contact with the vapors in the refluxing operation, a large proportion of the vapors are refluxed and the very light constituents produced in the cracking operation are concentrated in the pressure distillate.
- 15 The high degree of refluxing employed is, in one aspect, characteristic of the present invention. Where the refluxing operation is carried out with the direct introduction of cool fresh oil into the vapors therein, the degree of refluxing employed may be measured by the ratio between the rate at which fresh oil is so supplied and the rate at which distillate is taken off. Another measure of the degree of refluxing employed is the degree of concentration of the very light constituents in the pressure distillate. For example, pressure distillates are obtained in carrying out the present invention of which more than about 20% boils off up to 221° F. and more than about 40% up to 284° F. These hydrocarbon pressure distillates having this high content of very light constituents are also characteristic of the present invention.
- 30 Where cool fresh oil is supplied to the refluxing operation in direct contact with the vapors therein, and then supplied to the pressure still with the reflux admixed therewith, oil is withdrawn from the still charge to maintain it approximately constant as the operation continues. With the high degree of refluxing employed in carrying out the invention and with this high rate of supply of fresh oil, the percentage of distillate off on the total charge is relatively low, for example it may approximate 30% or somewhat more, and the withdrawal of oil from the charge thus makes prolonged operation possible, even with easily cracking charging stocks, because the pitch concentration of the charge is maintained below saturation or is allowed to build up only at a slow rate.
- 35 Where the refluxing operation is effected by external cooling of the vapors therein, fresh oil, which may be preheated, may be supplied to the still and oil withdrawn from the still charge, the rate of supply of fresh oil and of withdrawal of oil from the charge being regulated to maintain the pitch content of the charge below saturation, or fresh oil may be supplied at a somewhat reduced rate and oil may be withdrawn from the still charge at a reduced rate, or not at all, and the operation carried out in a batch or semi-continuous manner. In such an opera-

tion, the distillate taken off on the total charge may approximate 40% or somewhat more.

The invention will be further described in connection with the accompanying drawings which illustrate in a diagrammatic and conventional manner an apparatus adapted for carrying out the process of the invention. The pressure still illustrated in the drawings is of the general construction and operation described in United States Letters Patent No. 1,285,200 granted to the Sinclair Refining Company, November 19, 1918 on the application of Edward W. Isom. The pressure still system illustrated in the drawings is shown in elevation and partly in section with parts broken away.

Referring to the drawings, the pressure still comprises a bulk supply tank 1 and heating tubes 2, the heating tubes being arranged in the heating flue of a furnace 3 and the bulk supply tank being arranged away from the furnace, a circulating pump 4, and circulating connections 5, 6 and 7 connecting successively the bulk supply tank, the circulating pump and the lower end of the heating tubes, and the upper end of the heating tubes and the bulk supply tank. Arranged above the bulk supply tank is a reflux tower 8 provided with baffles 9. The reflux tower, the bulk supply tank, and the various circulating connections may be suitably lagged to prevent heat loss. A vapor line 12 is arranged to conduct vapors from the vapor dome on the bulk supply tank to the lower end of the reflux tower and a reflux return line 11 is arranged to discharge reflux and admixed fresh oil from the lower end of the reflux tower into the upper end of the circulating connection 5 on the suction side of the circulating pump. From the upper end of the reflux tower vapors escape through the vapor line 10 to the condenser 13 which discharges into a receiver 14 provided with a distillate outlet 15 and a gas outlet 16. The pressure in the still may be regulated by a valve 17 arranged between the reflux tower and the condenser, or it may be regulated by suitable valves arranged beyond the condenser. A spray-head 18 is arranged in the upper end of the reflux tower to which fresh oil is supplied through connection 19 which is provided with control valve 20. A connection 21 is arranged for supplying cool oil to the bearings of the circulating pump 4 to cool and protect them. A connection 22 is provided for pumping out and charging the still, and a tar draw-off connection 23 is arranged for withdrawing tar laden oil during the operation of the still. In the furnace 3, one or more blowers 24 are arranged to withdraw relatively cool heating gases from near the exit flue 25 of the furnace and to return them for admixture with the hot gases fresh

from the firebox 26 before the admixed gases pass over the heating tubes 2 arranged in the furnace.

The invention will be further illustrated 5 by the following specific examples of operations carried out in accordance with the present invention in apparatus of the type illustrated:

In one such operation, the pressure still 10 was initially charged with about 8000 gals. of gas oil and brought to an operating pressure of about 125 lbs. per sq. in. The gas oil charging stock had a gravity of about 30.2° Bé. and boiled off 10.0% up to 500° F. 15 and 29.7% up to 600° F. and had a pour test of 65. The temperature of the heating gases as they first contacted with the heating tubes was maintained at about 1900° F. During the run the head temperature at the 20 top of the tower averaged about 423° F. and was controlled by the introduction through the tower of a gas oil character stock having a gravity of about 33.5° Bé. and boiling off about 1.8% up to 450° F. 25 about 13.2% up to 500° F. and about 70% up to 600° F. and having a pour test of about 5. The rate of supply of fresh oil to the top of the tower averaged about 269% of the rate at which distillate was taken off. 30 Initially distillate was taken off at the rate of about 680 gals. per hour, and, before the concentration of pitch in the still charge reached saturation, the withdrawal of tar was begun, and the rate of distillate off was 35 decreased. Beginning in the sixth hour of operation, tar having an average gravity of about 28.3° Bé. was drawn for about 22½ hours at an average rate of about 995 gals. per hour and distillate was taken off during 40 this period at an average rate of about 450 gals. per hour. The run lasted 29 hours and during this time about 39,600 gals. of feed oil were introduced and about 14,470 gals. of distillate were taken off. The uncon- 45 densed gases escaping from the receiver amounted to about 70.6 lbs. per hundred gals. of distillate. The distillate had a gravity of 58.0° Bé. and boiled off 22.4% up to 221° F., 78.6% up to 400° F., 87.8% up to 50 450° F. with an end point of 508° F.

In another such operation, the pressure still was initially charged with about 8000 gals. of the same initial charging stock and was brought to an operating pressure of 55 about 125 lbs. per sq. in. The temperature of the heating gases as they first contacted with the heating tubes was maintained at about 1900° F. As distillate was taken off, fresh gas oil was supplied to the top of the 60 reflux tower at an average rate of about 278% of the rate at which distillate is taken off, the towerhead temperature being maintained at an average of about 431° F. This gas oil had a gravity of about 34.1° Bé. and 65 boiled off about 1.9% up to 450° F., about

15.2% up to 500° F. and about 70.9% up to 600° F. and had a pour test of 0. Until the withdrawal of tar was begun, distillate was taken off at a rate of about 606 gals. per hour. Beginning in the sixth hour of 70 operation, tar was withdrawn at a rate of about 1030 gals. per hour for 23 hours during which period distillate was taken off at a rate of about 487 gals. per hour. The run lasted 28½ hrs. during which time about 75 40930 gals. of gas oil were supplied to the tower, 14680 gals. of distillate being taken off. About 65.3 lbs. of gas per hundred gals. of distillate were produced. The distillate had a gravity of about 57.9° Bé. and 80 boiled off 24.6% up to 221° F., 77.2% up to 400° F. and 98.3% up to 450° F. with an end point of 510° F.

In carrying out the present invention, the concentration of light constituents in the 85 distillate may be increased by increasing the rate at which fresh oil is supplied to the reflux tower. When the rate of supply of fresh oil to the reflux tower is increased the rate at which distillate is taken off is reduced 90 and the percentage of distillate on the total still charge is reduced, but up to a certain point the production of gasoline character and very light hydrocarbon oil constituents is not decreased and may even be increased 95 to a substantial degree. The furnace temperatures employed may be as low as 1500° F. or even lower, and for the purpose of maintaining such low furnace temperatures it is advantageous to recycle a part of the 100 relatively cool heating gases leaving the heating flue of the furnace and to admix them with the hot products of combustion fresh from the fire-box before they pass through the heating flue, passing the mixture of tempered gases through the heating flue, so that a high temperature promoting efficient combustion may be maintained in the firebox proper while a relatively low 105 temperature is maintained in the heating flue. With more easily cracked charging stocks, the rate of production of light constituents is relatively high, but the process of the invention is also applicable to relatively less easily cracked charging stocks 110 by increasing the rate of refluxing and concentrating the light constituents in the distillate taken off. In such an operation, however, the rate at which distillate is taken off may be reduced due to the slower rate 115 of production of the desired light constituents. By employing somewhat increased pressures, the rate of vaporization in the pressure still can be reduced, reducing the amount of constituents to be refluxed, so that the proportion of heat applied to the cracking reaction proper may be increased. In this way, the furnace temperatures employed may also be decreased by increasing the 120 pressure. Higher pressures also assist in 125 130

improving the fractionation effected in the reflux tower, and are useful in the treatment of less easily cracked charging stocks in accordance with the invention.

5 I claim:

1. A method of cracking heavier hydrocarbon oils for the production of light hydrocarbon oils containing very light constituents in high concentration, which comprises distilling heavier oil under pressure at a cracking temperature, subjecting the vapors of the cracked oil to a refluxing operation, and introducing fresh oil into the refluxing operation in direct contact with the vapors therein at a rate greater than about 190% of the rate at which distillate is taken off.
2. A method of cracking heavier hydrocarbon oils for the production of light hydrocarbon oils containing very light constituents in high concentration, which comprises distilling heavier oil under pressure at a cracking temperature, subjecting the vapors of the cracked oil to a refluxing operation, and introducing fresh oil into the

refluxing operation in direct contact with 25 the vapors therein at a rate between about 190% and 300% of the rate at which distillate is taken off.

3. A method of cracking heavier hydrocarbon oils for the production of light hydrocarbon oils containing very light constituents in high concentration, which comprises distilling a charge of heavier oil under pressure at a cracking temperature, subjecting the vapors to a refluxing operation, introducing into direct contact with the vapors in the refluxing operation fresh oil at a rate of more than about 190% of the rate at which distillate is taken off, withdrawing oil from the charge, and regulating 30 35 40 45 the rate of supply of fresh oil and the rate at which oil is withdrawn from the charge so that the percentage of distillate taken off on the total charge including the fresh oil supplied thereto does not substantially exceed 30%.

In testimony whereof I affix my signature.

EUGENE C. HERTEL.
